CLAIM

I claim the ornamental design for furniture with drawers, as shown and described.

DESCRIPTION

FIG. 1 is a front perspective view of the furniture with drawers in accordance with the present invention;

FIG. 2 is a top plan view of the furniture with drawers of FIG. 1;

FIG. 3 is a front elevation view of the furniture with drawers of FIG. 1;

FIG. 4 is a first side elevation view of the furniture with drawers of FIG. 1;

FIG. 5 is a back elevation view of the furniture with drawers of FIG. 1;

FIG. 6 is a second side elevation view of the furniture with drawers of FIG. 1;

FIG. 7 is a bottom plan view of the furniture with drawers of FIG. 1;

FIG. 8 is an enlarged view of a portion of a circular handle of 8-8 of FIG. 3; and,

FIG. 9 is an enlarged view of a portion of a jewel-filled channel of 9-9 of FIG. 3.

The dash-dash broken lines shown in the drawings represent portions of the article that form no part of the claimed design. The dash-dot broken lines shown encircling the front circular feature of the claim represent boundaries of the claim and form no part thereof.

1 Claim, 3 Drawing Sheets
